UNITED STATES PATENT OFFICE.

EUGENE TERRY, OF ITHACA, NEW YORK, ASSIGNOR OF ONE-HALF TO LUCIEN AUGUSTUS WAIT, OF ITHACA, NEW YORK.

PICK.

No. 902,627.

Specification of Letters Patent.

Patented Nov. 3, 1908.

Application filed June 9, 1908. Serial No. 437,474.

To all whom it may concern:

Be it known that I, EUGENE TERRY, a citizen of the United States, residing at Ithaca, in the county of Tompkins and State of New York, have invented certain new and useful 5 Improvements in Picks, of which the following is a full, clear, and exact description, such as will enable others skilled in the art to which it appertains to make and use the 10 same.

This invention relates to improvements in implements in the nature of hand tools, such as picks, axes, hammers, sledges and similar tools.

One of the objects thereof is to provide an 15 implement of the above character which will possess the qualities of efficiency and durability to a higher degree than have similar implements as hitherto constructed.

Another object of the invention is to provide a hand tool which may be more effectively used by a workman and with less tax- 20 upon his energy, due to the fact that jars which are caused by the contact of the implement with the work are substantially 25 eliminated.

A further object of the present invention is to provide a construction whereby the 30 handles may be more firmly secured to the body portions or heads, and wherein there is less liability of said parts becoming loose or detached through decay.

Other objects will be in part obvious and in part pointed out hereinafter.

The invention accordingly consists in the 35 features of construction, combinations of elements and arrangement of parts, which will be exemplified in the construction hereinafter described, and the scope of the application of which will be indicated in the 40 appended claims.

In the accompanying drawing wherein 45 there is illustrated one of the various possible embodiments of my invention, Figure 1 is a view in elevation thereof. Fig. 2 is a similar view of a slightly different embodiment of the invention.

Similar reference characters refer to similar parts throughout the several figures of 50 the drawing.

The handle of the pick is indicated at 1, said handle being preferably constructed of wood, as is usual in such implements. This handle terminates short of the head 2, as 55 shown, and is connected therewith by means

of a pair of members or arms 3 and 4. These arms are preferably constructed of spring metal, and have their upper ends fitted to a portion of the lower end of the handle and are firmly secured thereto, as by 60 means of bolts or rivets such as shown at 5. These arms, as shown, diverge slightly from their points of engagement with the handle, and have their lower ends offset as 6, said offset portions lying in contact with the 65 head, and are secured thereto by means of clamp screws 7 threaded into the head or, if desired, by bolts or rivets passing entirely through the pick head or they may be secured thereto by welding or by any other 70 effective means.

In Fig. 2 of the drawings a slightly different embodiment of the invention is shown, in that the spring arms 3 and 4 are integrally 75 connected at their lower ends, the part connecting said arms lying in contact with the head and being secured thereto as by means of clamp screws 8 or by bolts or rivets passing entirely through the head or by welding or any other effective means.

The offsets of the arms will preferably be embedded in the pickhead so as to form shoulders which will relieve the bolts or rivets when striking with either end of the pickhead as shown in the drawings.

In the use of the pick which is shown herein as a typical embodiment of my invention, the spring arms which are interposed between the handle and the head will operate to prevent any jar from reaching the user, by absorbing the vibration of the handle when the pick is swung against the work.

Another advantage inherent in the present construction, resides in the fact that inasmuch as the handle is not extended through the pickhead, as is usual in such constructions, the liability of the same to become decayed and therefore loosened in its socket is entirely eliminated. Further, it will be obvious that by reason of the resilience or flexibility of the connection of the handle with the head, the points of the pick will retain their sharp edges for a longer period of time than have the points of picks as heretofore constructed. Another apparent advantage is that the points being readily detachable from one another, a broken or otherwise disarranged part may be discarded and a new part substituted without a loss of the entire implement.

110

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

10 It is also to be understood that the language used in the following claims is intended to cover all of the generic and specific features of the invention herein described and all statements of the scope of the invention 15 which, as a matter of language, might be said to fall therebetween:

Having described my invention, what I claim as new and desire to secure by Letters Patent, is:—

20 1. In an implement of the class described, in combination, a handle extending towards said blade and terminating short of the same, a pair of divergent spring arms secured to said handle, and means for securing the opposite ends of said arms to said head.

25 2. The herein described improvement in

handtools, such as picks, axes, hammers, sledges or similar tools comprising, in combination, a head, a handle extending towards said head, but terminating short of the same, and a pair of oppositely disposed, divergent resilient arms, the upper ends of which partially embrace the lower end of said handle, means for fastening said arms securely to said handle, the lower ends of said arms being offset to engage said head, and bolts or similar means for securing offset portions of the arms to the head.

3. In a tool of the class described, in combination, a head provided with one or more recesses, a handle terminating short of said head, and a pair of divergent resilient arms secured to said handle and having their lower ends lying in said recesses and secured to said head.

In testimony whereof I affix my signature, in the presence of two witnesses.

EUGENE TERRY.
